UNITED STATES PATENT OFFICE.

GORDON H. BURKE, OF PLYMOUTH, NEW HAMPSHIRE.

SPRING-HEEL FOR HORSE AND MULE SHOES.

1,317,070.

Specification of Letters Patent. Patented Sept. 23, 1919.

Application filed November 27, 1917, Serial No. 204,191. Renewed March 12, 1919. Serial No. 282,194.

To all whom it may concern:

Be it known that I, GORDON H. BURKE, a citizen of the United States of America, residing at Plymouth, in the county of Grafton, State of New Hampshire, have invented certain Improvements in Spring-Heels for Horse and Mule Shoes, of which the following is a description, reference being had to the accompanying drawings, forming a part

10 thereof.

The object of the invention is to provide, as an article of manufacture and as an attachment applicable to old and more or less worn or new horseshoes, a device embodying 15 a spring heel and rear calks which may be struck from plate metal, of uniform thickness, and may be applied effectively and securely to the shoe, with a minimum of manipulation, by the ordinary or moderately 20 experienced blacksmith or farrier.

Further objects and advantages of the invention will appear in the course of the following description, the same consisting in a simple and inexpensive construction and 25 arrangement of parts of which a preferred form is illustrated in the drawings, in which—

Figure 1 is a bottom plan view of the device as seen when applied to the shoe;

30 Fig. 2 is a top plan view also including the shoe and showing in dotted lines the positions of the forward lateral projections or ears as seen prior to the application of the article to the shoe;

35 Fig. 3 is a side view of the attachment, also as seen when applied to the shoe; and

Fig. 4 is a plan view of the blank as seen when struck from the plate.

In some respects the device forming the 40 subject-matter of this invention is similar to that set forth in the patent of this applicant, No. 1,170,218, granted Feb. 1, 1916, in that, like the former device it is constructed of a sufficiently resilient and resistant spring metal, such as steel or any other metal, and 45 is of substantially U-shape with the cross bar or loop of the U disposed at the heel of the horseshoe (when in use) and with the upwardly extending arms provided with termini-

50 nal ears, or inwardly extending projections, which are sufficiently pliable to adapt them to be bent around the inner edges of the sides of the horseshoe to form holding clips, the body portion of the device, springing at

55 a point adjacent to said clips, being deflected from the under surface of the shoe, to per-

mit of a yielding movement of the same toward and from the plane of the shoe as the weight of the animal comes upon or is removed therefrom.

In the present construction the device is adapted to be struck from a flat sheet or plate of metal of uniform thickness to form a blank as illustrated in Fig. 4, which embodies the general U-shape as above noted 60 with the loop or cross-bar 10 curved or arched forwardly both at its forward and rearward edges, to lie fairly within the contour of the shoe 11 at the heel, and the forwardly extending arms 12 follow approximately 65 the curvature of the sides of the shoe and terminate in inwardly projecting ears 13 which are normally in the plane of the body portion of the device but are adapted to be bent upwardly and outwardly 70 to the positions shown in Figs. 1 and 2 (in full lines in the latter) to engage the inner edges and upper surfaces of the sides of the shoe. In the construction illustrated the arms of the device may be arranged to underlie 75 the rearmost nail-holes 14 of the shoe and may be provided with corresponding and registering openings 15 through which the rearmost nails, employed for securing the shoe in place, may be driven, but this is 80 optional and not essentially necessary to the proper securing of the attachment to the shoe, for the reason that the length of the arms of the attachment is regulated so as to engage the shoe at the point of greatest 85 width thereof. Hence displacement forwardly or rearwardly is prevented by the curvature of the inner edges of the sides of the shoe in front and in rear of the points 90 of engagement of the clips. The portions 95 of the attachment immediately adjacent to the clips, shown at 16, lie snugly in contact with the under surface of the shoe, and in rear of this clip, to-wit, at the point indicated 17, the arms of the attachment are 100 slightly deflected downwardly to cause a divergence of the body portion from the plane of the under surface of the shoe, this divergence progressing rearwardly.

Also forming a part of the blank thereof 105 are outwardly extending ears 18 formed integral with the U-shaped body portion of the attachment and substantially as continuations of the loop or cross-bar 10 of the U, and which are adapted to be bent downwardly, as indicated in Figs. 1 and 3, to 110 form heel calks, which thus take the place

of the ordinary calks formed upon or attached to the horseshoe, and when the attachment is applied to a worn or old horseshoe, the said supplemental calks supply the deficiency due to the wearing away of calks which may ordinarily have been formed on the shoe, and thus restore the efficiency of the shoe in that respect, while adding the advantage of the spring-heel otherwise.

10 It is obvious that the device embodying the principles and construction described can be constructed at a comparatively negligible cost outside of that of the metal itself, in that it is adapted to be formed, practically ready for application to the shoe, by a single stroke of the die. The only additional manipulation is that incident to bending the calk members, this can be done at the same time that the blank is formed, 20 should it be found desirable to follow that course. The advantage in deferring this operation until the attachment is applied to the shoe, just as the bending of the forward ears is deferred until it is necessary to make 25 application, is that it permits of the stacking and packing of the attachments in compact form so as to occupy the minimum space in storage and shipment.

Having described the invention what is 30 claimed is:

1. As an article of manufacture, a spring-heel attachment for horseshoes of any type,

the same consisting of a U-shaped plate of substantially uniform thickness, provided at the extremities of its arms with inward and 35 at opposite sides of its loop with outward pliable projections.

2. As an article of manufacture, a spring-heel attachment for horseshoes of any type, 40 the same consisting of a U-shaped plate of which the forwardly extending arms are provided with front and rear lateral projections.

3. As an article of manufacture, a spring-heel attachment for horseshoes of any type, 45 the same consisting of a U-shaped plate of which the forwardly extending arms are provided with terminal lateral pliable ears, and calks carried by the plate at the rear portions of said arms. 50

4. As an article of manufacture, a blank for a spring-heel attachment for horseshoes, the same being struck from a plate of metal and consisting of a substantially U-shaped body portion provided with forward inwardly extending and rearward outwardly extending ears of even thickness with and lying in the plane of said body portion. 55

This specification signed and witnessed this 10th day of November, A. D. 1917.

GORDON H. BURKE.
